UNITED STATES PATENT OFFICE.

JOHN M. LINSCOTT, OF WORCESTER, MASSACHUSETTS.

LET-OFF MOTION FOR LOOMS.

SPECIFICATION forming part of Letters Patent No. 485,330, dated November 1, 1892.

Application filed January 28, 1890. Serial No. 338,344. (No model.)

To all whom it may concern:

Be it known that I, JOHN M. LINSCOTT, a citizen of the United States, and a resident of Worcester, in the county of Worcester and State of Massachusetts, have invented a new and useful Improvement in Let-Off Motions for Looms, of which the following is a specification, reference being had to the accompanying drawings, representing such portions 5 of a loom as embody my invention, and which form a part of this specification.

Figure 1 represents a rear elevation of a portion of the loom, showing a part of the warp-beam and the connected mechanism by which the delivery of the warp is regulated. Fig. 2 is a side elevation of the same portion. Fig. 3 is a top view thereof. Fig. 4 is a sectional view of the roll, to which a sliding motion is imparted in order to vary the speed of 10 the warp-beam. Fig. 5 is an elevation of the sliding roll, represented in Fig. 4 in sectional view.

Similar letters refer to similar parts in the different figures.

My invention relates to that portion of a loom known as the "let-off," by which the warp is unwound or delivered from the warp-beam during the process of weaving; and it consists in the arrangement and construction 25 of the operating parts, as hereinafter described, and specifically pointed out in the subjoined claims.

Referring to the accompanying drawings, A denotes a portion of the loom side or frame.

35 B is a portion of the beam upon which the warp is wound.

C is the whip-roll, over which the warp is carried to the harnesses in the usual manner.

D represents a worm-gear attached to the 40 shaft D', to which the warp-beam B is also attached.

E is a vertical shaft journaled in suitable bearings in a framework F, which in the present instance is attached to the loom side A. 45 Upon the vertical shaft E is a worm E' and a ratchet-wheel E², and immediately below the ratchet-wheel E² is a disk E³, turning loosely on the shaft E and carrying the pawls a a a a, which are pivoted upon the disk E³ and engage the ratchet-wheel E². From one side of the disk E³ a radial arm E⁴ extends, and with the radial arm E⁴ a band G is connected by

means of a hook or clasp b, which is capable of sliding along the arm E⁴. The band G is carried over the flanged guide-roll H and attached at its opposite or lower end with the treadle I, pivoted at I' to the end of an arm attached to the frame of the loom and having an angular motion imparted in one direction by the cam J upon the picking or lower 55 shaft K of the loom. The cam J is a two-leaved cam, and at each revolution of the shaft K the lever or treadle I is depressed twice, imparting an angular motion to the radial arm E⁴ and disk E³ and through the 60 pawls a to the ratchet-wheel E², shaft E, and worm E', causing the warp-beam to turn and let off a portion of the warp wound theron. As the cam J rotates, allowing the treadle to rise, the motion of the disk E³ and pawls a 65 are reversed by means of a spring L, which is attached to a rigid portion of the framework and also to a radial arm L', extending from the disk E³, the pawls in their reverse movement sliding over the teeth of the ratchet-wheel E². At each "pick" of the loom, therefore, the treadle I is moved downward, causing an angular motion of the disk E³ and 70 imparting an intermittent rotary motion to the worm E' and warp-beam and letting off a portion of the warp, the warp-beam remaining at rest during the reverse movement of the disk E³, band G, and treadle I by means of the spring L.

A uniform movement of the worm E' will 75 cause a uniform angular movement of the warp-beam; but as the diameter of the warp upon the beam B is constantly decreasing it will be necessary to gradually increase the angular movement of the beam as the warp 80 is unwound in order to secure a uniform delivery of the warp. In order to accomplish this purpose, I place the guide-roll H upon a sleeve M, which has a sliding motion upon a square shaft N, which is supported by the 85 frame F. Resting upon the warp on the beam B is a plate O, from which a rod or standard O' extends upward, moving in ways in the arms c c, projecting from the frame F. The upper end of the rod or standard is bent or 90 carried forward, and attached thereto is the triangular frame P, the inclined or oblique edge P' of which bears against the end of the sleeve M. As the warp is drawn from the 95 100

beam, the plate O, with its connected stand and triangular frame P, is allowed to fall by its own weight, the oblique edge P' gradually pushing the sleeve M along the square shaft N, carrying the guide-roll H, and with it the band G, thereby moving the hook or clasp b along upon the arm E⁴ and increasing the angular motion of the disk E³, and thereby imparting a greater movement to the worm E and warp-beam B, the increased angular movement of the warp-beam B being arranged to compensate for the decreased diameter of the beam.

R denotes weights placed upon the rod or standard O' to insure the falling of the plate O as the warp is removed from the beam.

The triangular frame P consists of the upright bar d and the oblique bar e, hinged at f to the upright bar and held in position by the slotted arc g and binding-screw h, allowing the angle of the oblique bar to be varied in order to vary the movement of the sliding sleeve M on the square shaft N.

The band G is attached to an eyebolt j, which is attached to the lever or treadle I, and the treadle I is provided with a row of holes k, allowing the distance between the eyebolt j and the cam J to be varied, thereby causing a variation in the angular motion of the disk E³. The ratchet-pawls a a a a are arranged with unequal spaces between them, varying by the space of one-fourth of a tooth of the ratchet-wheel, causing an angular motion of the disk equal to one-fourth of a tooth of the ratchet to move the ratchet.

Instead of the arrangement of pawls a a, placed at unequal distances apart, any of the usual and well-known forms of frictional connection may be employed between the disk E³ and the vertical shaft, by which the slightest motion of the disk E³ can be imparted to the shaft E. When a full beam of warp is placed in the loom, the plate O is placed upon the surface of the warp, the hook or clasp b is placed at the outer end of the radial arm E⁴, and the eyebolt j is attached to the treadle I at such distance from the cam J as to impart the requisite motion to the band G and the radial arm E⁴, projecting from the disk E³, and the oblique edge P' of the triangular frame P is made to bear against the sleeve M, so that as the plate O falls by the removal of the warp the edge P' will cause the sleeve M and roll H to move on the square shaft N and push the hook or clasp b along the radial arm E⁴, thereby increasing the angular motion of the disk E³.

What I claim as of my invention, and desire to secure by Letters Patent, is—

1. In a let-off for looms, the combination, with a warp-beam, of a worm-gear and worm-shaft, said shaft having an intermittent motion corresponding with the picks of the loom, substantially as described, through connected operating mechanism, a plate upon the warp on the warp-beam, and an oblique bar raised and lowered by said plate, said oblique bar being operatively connected with the worm-actuating mechanism, substantially as described, whereby the angular motion of said worm is varied as the warp is unwound from said beam, substantially as described. 60 65 70

2. In a let-off for looms, the combination, with a warp-beam, of a worm-gear and a worm-shaft, as described, by which said beam is turned, a disk provided with a radial arm and pivoted upon said shaft and operatively connected therewith, substantially as described, a vibrating treadle, a cam actuating said treadle, a band connecting said treadle and said radial arm, and a flanged guide-pulley, over which said band passes, said guide pulley or roll having a sliding motion, whereby the position of said band is changed relatively to said radial arm, substantially as described. 75 80 85

3. In a let-off for looms, the combination, with the disk E³, provided with a radial arm E⁴, of a band G, connecting said arm with a vibrating lever or treadle, a vibrating treadle, and an actuating-cam, a flanged guide-roll 90 having a sliding motion by which the position of said band is changed relatively to said radial arm and the angular motion of said disk is varied, and an oblique bar supported by the warp upon the warp-beam and operating to slide said roll as the oblique bar is allowed to fall by the removal of the warp from the warp-beam, substantially as described. 95

4. In a let-off for looms, the combination, with the warp-beam, of a worm-gear D, a worm-shaft E, provided with a worm E', ratchet-wheel E², disk E³, carrying pawls a a a a and provided with a radial arm E⁴, treadle I, cam J, connecting-band G, connecting said treadle with said radial arm and adjustably attached to said treadle, a flanged guide-roll capable of a sliding motion, an oblique bar e, with its edge operating to slide said guide-roll, a standard O', carrying said oblique bar, and a plate O, resting upon the warp upon the warp-beam, substantially as described. 105 110 115

Dated at Worcester, in the county of Worcester and State of Massachusetts, this 22d day of January, 1890.

JOHN M. LINSCOTT.
